VAPORIZER

Filed Dec. 31, 1935

UNITED STATES PATENT OFFICE

2,088,743

VAPORIZER

Louis P. Heckel, Santa Monica, Calif., assignor to
Curtis P. Heckel, Santa Monica, Calif.

Application December 31, 1935, Serial No. 56,928

2 Claims. (Cl. 128—192)

This invention relates to heaters and inhalers and has for an object the provision of a medicament container and vaporizer by means of which medicament in a vaporous state can be discharged in a downward direction from a canopy where it can be inhaled by a patient lying in bed.

A further object is to provide a heater and inhaler in which the means employed for converting the medicament into vapor will be characterized by a structure by means of which an up-draft will be induced at the vaporizing zone of a heater and the force of the induced draft employed to insure forced downward discharge of the vapor when the hood is lowered relative to the head of the patient and the vapor thereby effectively distributed at a position where the full benefit thereof can be had when inhaled.

Another object is to provide a heater and inhaler having a vapor discharge hood, the design, form and construction of which will enable the vapor to occupy an area of large proportion, in which area the head of the patient is adapted to be disposed, the construction of the device being otherwise such that the vapor will be confined against lateral displacement when in transit between the vaporizer and said hood.

Another object of the invention is to provide means for simplifying the work of inserting a charge of medicament in the vaporizing chamber of the device.

A further object is to provide a heater and inhaler in which an ordinary incandescent lamp can be used for subjecting the medicament to a vaporizing temperature.

A further object is to provide a heater and inhaler having means by which vertical adjustment of the hood can be effected as desired, whereby it can be closely related to the head of the patient.

A further object is to provide a heater and inhaler having means by which any vapor which may possibly condense upon discharge from the vaporizer will be trapped and prevented from falling upon the face of the patient.

In the accompanying drawing,

Figure 1 is a vertical section through a preferred embodiment of the invention with parts shown in full lines;

Figure 2 is a view in side elevation of the device showing the sections of the vaporizing chamber separated relative to each other for the introduction of a charge of medicament thereto;

Figure 3 is a transverse section on the line 3—3 of Figure 1;

Figure 4 is a section on line 4—4 of Figure 1.

In carrying the invention into practice, use is

made of a portable standard 10 having a flat base 11 adapted to rest upon a floor or other supporting surface, as shown in Figure 1. Said standard is formed with a vertical straight length section 12 on which a vaporizing chamber 13 is mounted. 5

The vaporizing chamber 13 comprises a vertically disposed cylindrical body having a lining 14 of heat insulating material such as asbestos. The body has a bottom 15 formed with an annular series of vertical draft passages 16 by means 10 of which air can be taken into the chamber as indicated by the arrows in Figure 1.

At the top, the chamber is provided with an inverted conical cover 17, the same being separable from the chamber or adjustable vertically relative thereto, as shown in Figure 2. When said cover is adjusted as just stated, the body of the chamber may be supported in a position of lowered adjustment by engagement of the body supporting bracket 18 with a horizontal branch 19 of standard 10 as also shown in Figure 2. The bracket 18 may be held in a fixed position on the extension 12 by a clamp bolt 20, the latter serving when adjusted to one position to enable the vaporizer body to be turned about the axis of the branch 12, at which time quick and convenient access can be had to the interior thereof when charging the chamber with medicament.

Within the chamber 13 at the center of the bottom 15 thereof is a heater 21, preferably in the form of an incandescent lamp of suitable wattage. This lamp is surrounded at its base by the aforesaid draft openings 16, and same directly underlies a medicament cup 22 which is supported by a wing 23, the latter having an annular series of openings 24.

At the apex of the inverted conical top 17 is attached one end of a conduit 25, the same curved outwardly at 26 and passed through a clamp collar 28 of the upper conical section 29 of a canopy 30. This canopy is provided with a depending skirt 31 of suitable fabric material.

The base 11 has a tubular portion 32 in which standard 10 can be raised and lowered, and same can be secured in an intended position of vertical adjustment by a clamping device 33.

The end of the conduit 25 to which the canopy section 29 is attached is provided with supporting arms 34 to the lower ends of which the upper open end of a condensation cup 35 is removably fitted, the upper end of said cup being disposed in spaced relation to the discharge end of the conduit as shown in Figure 1.

A patient to be treated may be seated beneath the large diameter canopy of the device and the

canopy lowered to either dispose the head in the canopy or in such relation thereto as will enable the generated medicament vapor to be freely inhaled. If desired, however, the patient can lie in bed and the canopy can be lowered as desired relative to the face of the patient.

When the canopy has been adjusted as above stated, the lamp 21 is lighted so as to generate sufficient heat to vaporize the medicament in the cup 22. By the action of suction induced by the heat of the lamp, air will be drawn into the chamber 13 from whence it passes into the conduit 25 by way of openings 24 in ring 23. In this manner, the vapor will be discharged into the hood at an effective velocity to provide a zone within the canopy in which a large volume of vapor will be constantly present in order that it can be freely inhaled by the patient. Any condensation passing from the conduit 25 will be caught by the cup 35 and thus held from direct contact with the face of the patient.

Various changes in the forms, constructions and design of the parts employed can be made without departing from the broad idea of a means to convert a volatile, or other suitable well known medicament into vapor and effect a discharge thereof from the vaporizing chamber by an up-draft formed in the chamber in the manner herein stated and the vapor passed to a location where it can be freely inhaled by the patient.

I claim as my invention:

1. In a device of the class described, a va-

porizing chamber having a heater therein; a medicament holder in the chamber above the heater, the chamber formed with a draft opening for admission of air to the chamber by suction induced by heat generated by the heater and to provide an up-draft in the chamber above and around the medicament holder; a vapor discharge conduit leading from the chamber above the medicament holder, and having a depending cover separably associated with the chamber to close the open top thereof; a vertical support; means for securing the discharge conduit to the support; means for mounting the chamber on the support for rectilinear movement vertically from a closed position to an open position relative to said cover, in order to render the medicament holder accessible; and means for releasably retaining the chamber in closed position.

2. In a device of the class described, a standard; a vaporizing chamber mounted on the standard and including a cover section having a discharge conduit secured to the standard, and a body section vertically adjustable on the standard from a closed position to an open position relative to the cover section so as to expose the interior of the body section; means for retaining the body section in closed position; means for generating vapor in the chamber; and means for effecting forced ejection of vapor from said chamber through said discharge conduit when the body section occupies closed position.

LOUIS P. HECKEL.
